HARRY CARDEN DESPARD, OF SYRACUSE, NEW YORK.

ELECTRICAL ATTACHMENT.

1,207,876.

Specification of Letters Patent. Patented Dec. 12, 1916.

Application filed April 24, 1915. Serial No. 23,631.

To all whom it may concern:

Be it known that I, HARRY C. DESPARD, a citizen of the United States, and resident of Syracuse, in the county of Onondaga, in the State of New York, have invented new and useful Improvements in Electric Attachments, of which the following, taken in connection with the accompanying drawings, is a full, clear, and exact description.

10 This invention relates to an electric attachment adapted particularly to be applied to ironing boards, although susceptible of attachment to tables and other similar articles.

15 In the use of electrically heated sad irons where, as is usual, the iron is connected to a wall or ceiling socket by a flexible cord carrying the wires, the cord is always in the operator's way, lying across and upon the board, interfering with the goods to be ironed and with the movements of the operator, and the primary object of this invention is to provide means for obviating this difficulty by the use of an intermediate 20 switch having means of securement to an ironing board, of such form and nature that the flexible cord hangs almost entirely off the edge of the board, out of the way of the operator and out of contact with the goods 25 to be ironed. A further advantage of the use of a switch adapted to be clamped to the board lies in the fact that the operator may at any time shut off or turn on the current to his iron, without moving from his 30 position at the ironing board.

35 Other objects relate to the details of construction of and the combination of elements such as the combination under a single cover of an electric switch and an electric receptacle or socket, suitably connected for combined operation.

40 Other and further objects and uses will appear from the following description, taken in connection with the accompanying drawings, in which—

45 Figure 1 is a perspective view of the device as applied to an ironing board and assembled in combination with a sad iron for use. Fig. 2 is a top plan view of the device. Fig. 3 is an end elevation of the same. Fig. 50 Fig. 4 is a cross section on line 4—4, Fig. 3.

55 In order that my invention may be clearly understood, I have shown a complete and operable assemblage of elements combined for use, including an ordinary ironing board or table —1— and an electrical sad iron

—2— of any usual and well known construction.

The sad iron is adapted to be connected by a flexible cord —3— to any suitable source 60 of electric current supply and, in the assemblage shown, an interposed switch and socket inclosed within a casing —4— is illustrated, said switch operably and electrically connected by a flexible cord —5— to a wall 65 socket —6—. The construction of the switch and receptacle or socket may be of any usual and well known character.

The switch —7— embodies suitable terminals —8— and —9— to which the wires of the 70 flexible cord —5— are attached. The socket —10— is separated from the switch by a suitable partition or block —11— of insulating material having openings for the passage of wires —12— and —13— suitably 75 connected to the switch and to terminals —14— and —15— of the socket —10—.

The casing —4— is preferably formed of metal or any other suitable and comparatively rigid strong material adapted to protect the inclosed portions of the switch and socket, which parts usually embody porcelain or other similar material as an insulating agent. The top and bottom —16— and —17— of the same are preferably removably secured 80 to the side and end walls, the top —16— being shown as connected thereto by means of screws —18—, and the bottom —17— having a similar means of connection. The bottom —17— preferably has a portion 85 —19— extending some distance beyond one end of the casing —4—, and the part —19— is provided with a laterally projecting arm —20— extending at substantially right angles to the direction of projection of the 90 part —19—, and the arm —20— has its intermediate portion —21— bent downwardly at substantially right angles to the arm and its end portion —22— return bent in substantially a parallel vertical plane 100 with the arm —20—, but forming an acute angle with the intermediate portion —21— so as to gradually converge toward the parts —19— and —20— as it extends from the portion —21— and having its tip —23— 105 bent downwardly somewhat so as to diverge from the part —19— toward its point of termination.

The parts —19—, —20—, —21—, —22— and —23— being formed of thin sheet metal, 110 have a certain amount of resiliency, whereby the parts —22— and —23— may be

sprung slightly from the parts —19— and —20— and will grasp tightly a portion of an ironing board or table with which they are adapted for sliding engagement, the offset portion —23— allowing easy insertion of the edge of the board and acting to automatically spring the arm —22— away from the arm —20—.

In actual assemblage, the cord —5— is provided at one end with a plug adapted to be secured to the wall socket —6— and its other end extends through the wall of the casing —4— and the respective wires are secured to the terminals —8— and —9—, which terminals are in turn electrically connected to the primary terminals of the switch —7—. The switch is insulated from the socket —10— and its terminals —14— and —15— are connected to respective primary terminals of the switch —7—.

The sad iron —2— has any usual and well known connection with the wires carried by the cord —3—, and the opposite end of the cord is provided with a plug —24— adapted for engagement with the socket —10—.

The clamping device constituting the portions —19—, —20—, —21—, —22— and —23— is slid over the end of the ironing board, the spring nature of the parts holding the casing —4— rigidly in place so that the cord —3— extending from the plug —24— lies off the side of the ironing board and the iron may be moved back and forth across the board without the necessity of the cord contacting with the goods, except possibly a very short portion adjacent its connection to the iron, and the cord is entirely out of the way of the operator and the

supply of current may be readily shut off or turned on as the iron may be too hot or too cold, by the operation of switch —7— through the usual button —25—.

Although I have shown and described one particular construction, assemblage, form and manner of operation of the parts, I do not desire to limit myself to any particular construction, assemblage, form or method of operation, as many changes may be made in the details of such features without departing from the spirit of this invention as set forth in the appended claim.

What I claim is:

In an apparatus of the class described, an iron adapted to be electrically heated, a socket, a switch element, clamping means in connection with said switch element for securing the same to an ironing table, flexible electric conductor connection between the switch element and the iron so that the iron may move in all directions relatively to the element, flexible electric conductor connection between the switch element and the socket so that the switch element may be positioned at any desired point relatively to the socket, said clamping means adapted to secure the switch element to an ironing table in such manner that the flexible conductor between the switch element and the iron hangs practically entirely off the edge of the table.

In witness whereof I have hereunto set my hand this 17th day of April, 1915.

HARRY CARDEN DESPARD.
